SLIP

Erwin Burns, Los Angeles, and Harry P. Wicker-
sham, Huntington Park, Calif.

Application January 7, 1935, Serial No. 664

11 Claims. (Cl. 24—263)

This invention relates to pipe handling devices and has particular reference to slips for use in the rotary table of a well drilling rig. A general object of the invention is to provide simple, practical slips having novel and effective means for gripping pipe and like objects.

Another object of the invention is to provide slips for use in a rotary table embodying a plurality of super-imposed cams or gripping dogs that automatically cam or move into tight gripping and holding engagement with the pipe when the slips assume the weight of the pipe.

Another object of the invention is to provide slips of the character mentioned in which the dogs or cams are simple members that may be easily removed for replacement, etc.

Another object of the invention is to provide slips of the character mentioned in which the slip bodies which carry the pipe gripping dogs or cams are simple and inexpensive of manufacture. The pipe gripping members or cams of the present invention have substantially disc shaped major portions whereby they may be carried in partially cylindrical openings in the inner face 25 of the slip body which openings may be easily and inexpensively drilled or provided in the body.

A further object of the invention is to provide slips of the character mentioned that are positive and dependable in operation and that may be easily manipulated.

Other objects and features of the invention will be more fully and better understood from the following detailed description of a typical preferred form and application of the invention, throughout which description reference is made to the accompanying drawing, in which:

Fig. 1 is a top plan view of a set of slips embodying the invention arranged in the spider or bushing of a rotary table or the like. Fig. 2 is an enlarged vertical detailed sectional view of one of the slips, and Figs. 3 and 4 are transverse detailed sectional views taken substantially as indicated by lines 3—3 and 4—4, respectively, on Fig. 2.

The present invention may be embodied in slips varying somewhat in character and in slips for use in rotary tables and rotary table spiders and bushings of different types. In the drawing we have illustrated the invention embodied in a set of three slips S designed for arrangement in the tapered opening O of a spider or bushing B of the type employed in the rotary table of a well drilling rig. It is to be understood that the invention may be embodied in other forms and in sets of two, four, or more slips. As the several slips S are identical, we will proceed with a de-

tailed description of one slip, it being understood that such description may apply equally well to the other slips S of the set.

The slip S provided by this invention includes, generally, a body 10 for arrangement in the opening O, and means 11 carried by the body 10 for gripping a pipe P.

The body 10 may be varied considerably in shape and construction without departing from the broader aspects of the invention. The particular body 10 illustrated in the drawing is an integral hollow member having a longitudinal opening or cavity 12. The slip body 10 is shaped to fit or operate in the opening O having its major external surface 13 convex and tapered downwardly and inwardly to cooperate with the wall of the opening. The upper and lower ends of the body 10 may be flat and horizontal and the opposite sides 14 of the body may be flat and substantially parallel. Radial corner faces 15 extend from the sides 14 to the inner face or surface 16 of the body. The radial faces 15 are adapted to cooperate with the corresponding faces 15 of adjacent slips S. The inner surface 16 of the body 10 is substantially vertical and is concave being cylindrically concaved concentric to the longitudinal axis of the opening O. A suitable handle H is pivoted to the body 10 at 17 to facilitate the easy handling and carrying of the slip.

The means 11 for engaging and gripping the pipe P is an important feature of the invention and is in the nature of a cam means comprising super-imposed cams or dogs 18 carried by the body 10 to cooperate with the pipe P. If desired, a single series of cams or dogs 18 may be provided on the slip body 10. However, it is preferred to provide a plurality of circumferentially spaced series of dogs 18 on each slip body 10. The cams or dogs 18 are arranged in vertical or longitudinal openings 19 in the inner side or face 16 of the body 10. In the particular form of the invention shown in the drawing there are three substantially equally spaced openings 19 for holding three series of dogs or cams 18. The dogs 18 or cams 18 are preferably alike or identical in shape and size. In accordance with the invention the bodies or major portions of the dogs 18 are partially disc shaped in plan elevation and have peripheries 24 which extend for more than 180°. The openings 19 are shaped to hold the major portions of the dogs 18, being in the nature of round or cylindrical bores which have sides open at the inner surface 16 of the body 10. The cylindrical walls of the openings 19 are each of 55

more than 180° in circumferential extent and the dogs 18 are proportioned so that their major portions are prevented from passing horizontally out of the openings 19. Lugs or tongues 21 are provided on the dogs to grip the pipe P and extend through the open forward sides of the openings 19 to project from the inner surface 16 of the body 10. The active inwardly facing ends 22 of the tongues 21 are preferably cylindrically concaved to substantially conform to the periphery of the pipe P. The active ends 22 of the tongues 21 are inclined downwardly and outwardly from the upper surfaces of the tongues providing the tongues with comparatively sharp upper edges 23 for biting into the pipe. The tongues 21 in projecting through the open sides of the openings 19 prevent the cams or dogs from turning about horizontal axes.

The cams or dogs 18 are super-imposed and directly supported one upon the other. In the preferred form of the invention the major portions of the dogs 18 are transversely bowed or curved, having curved contacting upper and lower surfaces 20. The dogs may readily tilt or pivot when the engagement of the tongues 21 with the pipe P causes the tongues to move downwardly. The series of dogs 18 are normally inclined upwardly and inwardly with respect to the longitudinal axis of the pipe P. The peripheral edges or peripheries 24 of the major portions of the dogs are bevelled or rounded to permit the free tilting or pivoting of the dogs. The series of dogs 18 are preferably supported in the openings 19 in a manner which allows them to readily rock or pivot. The openings 19 terminate at their lower ends at shoulders 25. Reduced openings 26 extend upwardly from the lower end of the body 10 to the shoulders 25. Pins 27 are inserted in the reduced openings 26 from their upper ends and have heads 28 bearing on the shoulders 25. The upper surfaces of the heads 28 are curved upwardly and inwardly or in the same direction as the upper and lower surfaces 20 of the dogs so that the lower sides 20 of the lowermost dogs 45 may evenly rest on the heads 28 when the dogs are in their normal positions. The pins 27 may be easily replaced or repaired if they become worn.

Means is provided for retaining the series of dogs 18 in the openings 19 and for limiting the extent of tilting or pivoting of the dogs. A retaining plate 30 is removably attached to the upper end of the body 10 by bolts or screws 31 and extends across the upper ends of the several openings 19 to retain the dogs in the openings. The retaining plate 30 may be counter-sunk in the upper end of the body 10. The series of dogs 18 are proportioned so that the upper sides 20 of the uppermost dogs are adapted to cooperate with the plate 30 to limit tilting or pivoting of the dogs. It is preferred to relate the parts so that the dogs 18 are prevented from pivoting to or beyond horizontal positions.

In employing the slips S of the invention the bodies 10 are arranged in the opening O so that their outer surfaces 13 may cooperate with the wall of the opening and so that the active ends 22 of the tongues 21 may engage the pipe P. When the weight of the pipe P is allowed to settle on the set of slips the tongues 21 engaging the pipe are caused to move downwardly. This downward movement of the tongues 21 of the several series of dogs 18 is accompanied by upward swinging or pivoting of the major portions 75 of the dogs. The dogs 18 in having transversely

curved upper and lower surfaces 20 may freely tilt or pivot in this manner. The pivoting of the dogs 18 cams or moves the active ends 22 of the tongues 21 into tight gripping cooperation with the pipe P. In practice the edges 23 of the tongues may bite into the pipe to dependably support the same. It is to be understood that the multiplicity of dogs 18 in each series is free to simultaneously pivot and cam into tight holding engagement with the pipe. Where each slip S is provided with a plurality of series of dogs 18 the pipe P is gripped at a multiplicity of circumferentially spaced points by the rows of superimposed dogs. The dogs 18 are effective in dependably gripping and holding the pipe P. When the pipe P is raised or moved upwardly the tongues 21 which are in active engagement with the pipe are also caused to move upwardly. This upward movement of the tongues 21 is accompanied by downward and inward pivoting of the dogs so that the dogs are automatically returned to their normal retracted positions when the pipe is moved upwardly. The automatic retraction of the dogs 18 frees the slips from the pipe allowing the slips to be readily removed from the rotary table opening O. The dogs 18 may be easily removed from the openings 19 by detaching the plates 30. The body 10 and the dogs 18 are simple and inexpensive of manufacture. Dogs 18 having tongues 21 of different lengths may be arranged in the openings 19 to adapt the slips for properly handling pipe of different diameters.

Having described only a typical form and application of our invention, we do not wish to be limited or restricted to the specific form and application herein set forth, but wish to reserve to ourselves any modifications or variations that may appear to those skilled in the art or fall within the scope of the following claims:

Having described our invention, we claim:

1. A slip for use in a rotary table including a body having an opening open at its inner side, and super-imposed dogs in the opening projecting from said inner side to contact a pipe, the dogs being transversely bowed to have curved 45 slidably contacting surfaces.

2. A slip for use in a rotary table including a body having an opening open at its inner side, super-imposed dogs in the opening having curved 50 contacting upper and lower surfaces, and tongues on the dogs projecting through the open side of the opening to contact a pipe.

3. A slip for use in a rotary table including a body having an opening open at its inner side, super-imposed cams in the opening curved in cross section to have curved cooperating upper and lower surfaces, tongues on the cams projecting through the open side of the opening to engage a pipe, and means supporting the cams for pivotal movement.

4. A slip for use in a rotary table including a body having an opening open at its inner side, super-imposed cams in the opening curved in cross section to have curved slidably cooperating upper and lower surfaces, tongues on the cams projecting through the open side of the opening to engage a pipe, and means supporting the cams in inclined positions where their tongues project upwardly and inwardly.

5. A slip for use in a rotary table including a body having an opening open at its inner side, super-imposed pivotable dogs in the opening curved in cross section to have curved slidably contacting upper and lower sides, tongues on the dogs projecting through the open side of the 75

opening to engage a pipe, means for normally supporting the dogs in inclined positions, and means for limiting pivotal movement of the dogs.

6. A slip for use in a rotary table including a body having a partially cylindrical opening open at its inner surface, and a plurality of substantially disc shaped super-imposed dogs in the opening having tongues projecting through the open side of the opening to engage a pipe.

10 7. A slip for use in a rotary table including a body having a partially cylindrical opening open at its inner surface, and a plurality of substantially disc shaped super-imposed dogs in the opening having curved contacting upper and lower surfaces, the dogs including tongues projecting through the open side of the opening to engage a pipe.

15 8. A slip for use in a rotary table including a body having spaced substantially vertical partially cylindrical openings open at its inner side, and multiplicities of super-imposed dogs in the openings having tongues projecting through the open sides of the openings to engage a pipe.

20 9. A slip for use in a rotary table including a body having an opening open at its inner side, super-imposed cams in the opening having curved cooperating upper and lower surfaces, tongues

on the cams projecting through the open side of the opening to engage a pipe, and means supporting the cams for pivotal movement, said means including a curved inclined seat at the lower end of the openings.

25 10. A slip for use in a rotary table including a body having an opening open at its inner side, super-imposed dogs in the opening of curved cross section to have curved slidably contacting surfaces, and tongues on the dogs projecting through the open side of the opening to contact a pipe, the ends of the dogs being curved to substantially conform to the pipe and having edges for gripping the pipe.

15 11. A slip of the character described including a body having an opening open at its inner side, a multiplicity of superimposed cams in the opening having their upper and lower surfaces curved downwardly and outwardly relative to said side of the body, and tongues on the cams projecting through the open side of the opening to engage a pipe, the said surfaces slidably cooperating to allow free relative movement between the cams during actuation and retraction of the cams.
